UNITED STATES PATENT OFFICE.

HENRY E. WINANS AND GEORGE N. WOODEN, OF NEWARK, NEW JERSEY.

SHOT-CONCENTRATOR.

SPECIFICATION forming part of Letters Patent No. 336,680, dated February 23, 1886.

Application filed June 20, 1885. Serial No. 169,281. (No model.)

To all whom it may concern:

Be it known that we, HENRY E. WINANS and GEORGE N. WOODEN, citizens of the United States, residing at Newark, in the county of Essex and State of New Jersey, have invented 5 certain new and useful Improvements in Shot-Concentrators; and we do hereby declare the following to be a full, clear, and exact description of the invention, such as will enable others skilled in the art to which it appertains to make and use the same, reference being had to the accompanying drawings, and to letters of reference marked thereon, which form a part of this specification.

15 This invention relates to improvements in devices used to regulate the flight of the load of shot from a cartridge, and is designed to cause the shot to be more accurately projected from the gun and prevent the same 20 from either massing together or scattering widely, the improved device allowing the shot to spread with regularity from the time the load leaves the gun until it reaches a point (usually about thirty yards) where it is no longer needed.

25 The invention consists in the device for regulating the flight of the shot, substantially as illustrated in the drawings, and described and claimed hereinafter.

30 In the drawings, Figure 1 is a side elevation of a shot-cartridge. Fig. 2 is a longitudinal section of a shot-cartridge with our improved shot concentrator or regulator arranged therein. Fig. 3 is an end elevation of the same; and Figs. 4 and 5 are a longitudinal section and side elevation, respectively, 35 of the concentrator illustrated in Fig. 3.

Similar reference - letters indicate corresponding parts in each of the views above described.

40 In the drawings, *a* is the cartridge-shell, *b* the powder-receptacle, *c* the shot-chamber, and *d* a wad separating the two. Near the open end of the cartridge-shell in the shot-chamber is the concentrator, which consists 45 of an outer shell, *e*, made of any suitable material, pasteboard being preferable, having one end, *e'*, cut or scalloped, as indicated in Figs. 5 and 6. Within the shell *e* is arranged another shell, *f*, shorter than the outer shell, and made preferably of tin. Across the face of the shell *f* are arranged four wires, *g*, *g'*, which cross each other at right angles, two, *g*, crossing in one direction, and two, *g'*,

55 in another, leaving openings between of about the same area. The wires cross the face of the shell *f* and extend in between the same and the shell *e*, as indicated in Fig. 5, by which arrangement they are held in place.

The object of notching or scalloping one end 60 of the casing or shell *e* is to permit it to spread by the force of the explosion when the load starts and hug the barrel, thereby insuring certainty of flight.

The peculiar arrangement and the number 65 of wires employed give the greatest effectiveness to the flight of the shot, allowing them to escape at the proper moment and in sufficient number.

Having described our invention, we desire 70 to claim the following:

1. A shot-concentrating device consisting of an outer casing having one end notched or scalloped, an inner shell arranged within said outer casing, and wires arranged across one 75 end of the inner shell, and extending in between the said inner shell and the outer casing, said device being adapted to be arranged in a shot-cartridge, for the purpose set forth.

2. A shot-concentrating device consisting 80 of an outer casing having one end scalloped, an inner shell arranged within said outer casing, and four wires arranged across the face of said inner shell, dividing the opening therein into spaces of approximately the same area, the 85 ends of said wires extending in between the outer and inner casing, said concentrating device being adapted to be arranged in a shot-cartridge, for the purposes set forth.

3. The combination, with a shot-cartridge, 90 of a shot-concentrating device consisting of an outer casing having one end scalloped, an inner shell arranged within said outer casing, and four wires arranged across the face of said inner shell, dividing the opening therein into 95 spaces of approximately the same area, the ends of said wires extending in between the outer and inner shells, substantially as and for the purposes herein set forth.

In testimony that we claim the foregoing 100 we have hereinunto set our hands this 9th day of June, 1885.

HENRY E. WINANS.
GEORGE N. WOODEN.

Witnesses:

OLIVER DRAKE,
OSCAR A. MICHEL.
